Hitchell, Chadwick & Kent Attns.

UNITED STATES PATENT OFFICE.

GEORGE S. BARROWS, OF PROVIDENCE, RHODE ISLAND, AND NICHOLAS W. PARK,
OF BROOKLYN, NEW YORK.

SAFETY CONTROLLER FOR GAS VALVES.

Application filed January 2, 1920. Serial No. 348,857.

To all whom it may concern:

Be it known that we, GEORGE S. BARROWS and NICHOLAS W. PARK, citizens of the United States, respectively, residing at Providence, in the county of Providence and State of Rhode Island, and at Brooklyn, in the county of Kings and State of New York, have invented certain new and useful Improvements in Safety Controllers for Gas Valves, of which the following is a specification.

This invention relates to flame-controlled gas valves. More particularly it relates to safety devices for gas burners, in which the ignition of gas is dependent on the existence of a flame at the orifice, which may be either the main flame or a pilot flame. Such a flame may be extinguished by wind, by temporary drop in gas supply pressure, or even by malevolent interference, following which the gas supplied to the burner upon a restoration of pressure or when turned on automatically as by a thermostat, or otherwise, will fail to be ignited, perhaps without the knowledge of any person, with ensuing disagreeable or damaging results. It is the object of the invention to prevent such by automatically preventing the flow of gas unless the igniting flame is burning. The objects of the invention are accomplished by arranging a valve which controls the gas supply in combination with means tending automatically to close it and means by which the igniting flame produces a reaction that holds the valve open automatically to permit the passage of gas while the flame is burning. This means embodies an electrical circuit which is made or broken by the movement of a thermostatic member actuated by heat from a flame predetermined as proper. It is part of the invention to construct the thermostat so that it is neither subject to the corrosion and distortion which results from being in the flame, nor subject to the uncertainty which attends the direction and intensity of radiation of heat from the flame; but is nevertheless so arranged as to be duly sensitive to the flame. It is a further object to make the apparatus of such a type that it can be light in weight, contained in small compass near the flame, and well protected. These and other objects are accomplished by supporting the thermostat on the pilot tube, within a screen and arranged to receive heat by conduction from

the flame, and to bend into contact with the pilot tube or other metallic element that conducts the heat to it from the flame and also serves as a conductor of electricity to control the gas valve and hold it open. When the pilot flame is not burning, the thermostatic element moves out of contact, thus breaking the circuit and letting the gas valve automatically close. The thermostat, being thus set so as to make the contact only when extremely hot from the direct conduction of heat, is further protected from acquiring a permanent distorted set from its coolings by a stop which limits its movement on cooling to a short distance, only great enough to make a good break. The invention may be embodied in other arrangements, some of which are set forth hereinafter. It is intended that the patent shall cover, by suitable expression in the appended claims, whatever features of patentable novelty exist in the invention disclosed.

In the accompanying drawings:

Figure 1 is a side elevation of a fragment of a radiator embodying the invention partly in diagram;

Figure 2 is a similar view on a larger scale of the safety thermostat and associated parts in medial section;

Figure 3 is an elevation of the end of the apparatus of Figure 2; and

Figures 4, and 5 are side elevations in medial section of modifications.

Referring to the drawings, which represent the invention arranged in combination with a gas radiator, having a burner set in the open air, so that escape of gas from the burner without ignition would introduce the gas into the apartment, 10 indicates the burner and 11 the radiator tubes. For igniting the gas whenever it is turned on, a pilot flame 12 supplied by a pilot tube 13 is provided, the main supply of gas to the burner 10 coming through the mixing device 14 from a gas supply pipe 15. Controlling the supply is a gas valve 16 tending always to fall against a seat 17 from which it may be lifted by the armature 18 of a magnet within the casing 19 whenever a current passes through the circuit 20. Such a current, from any suitable source, such as a low potential generator 21, may include in its circuit a serving thermostat 22 set in the apartment whose temperature is to be controlled automatically, arranged to close the circuit when the

temperature of the room falls to a predetermined point, thereby energizing the magnet and opening the gas valve, assuming that the circuit is complete elsewhere. These parts 5 may be of any suitable or ordinary construction, but it is a feature of the invention that the circuit is through a safety thermostat operated by the flame.

In the particular form illustrated in Figure 1, the main length of pilot tube 13 terminates far enough from the pilot burner orifice 24 to carry a block of insulating material 23 and a screen housing within which is an insulated tip or continuation 13' of the pilot tube, and the safety thermostat 26. The thermostat there illustrated is a light bi-metallic bar bent into U-shape with one limb of the U held in the insulating block by a set screw 30 to which an external wire of the circuit is attached, and with the other end 29 of the U adapted to make contact with the insulated tip section 13' of the pilot tube 13 which in turn is connected through screw 31 to another external 15 wire 20 of the circuit. The screen 25 may be a tubular, fine mesh cap held on the same block of insulating material by any convenient device, as by friction, with its closed outer end so positioned that the tip of the 20 pilot tube and its flame are close outside of it. The curved part of the U may be close to the flame, but within the screen. Experiment has disclosed that it is bad for the thermostat to stay in the flame; and that 25 even if it be closely adjacent to the flame, with the heat reaching it by convection and radiation from the flame, its action is uncertain. The arrangement illustrated, however, while availing of such help as may come 30 by way of radiation, provides as a main and certain element of the combination a direct metallic connection from the flame to the thermostat. This connection is the tube tip 13', through which heat flows by conduction 35 from the flame and the rate of such transfer of heat is fairly constant. The screen permits circulation of air past the thermostat but slowly. Corrosion of the thermostat is 40 reduced because it prevents to a great extent products of combustion from the flame, and moisture from the atmosphere reaching the thermostat. A stop or screw 31 mounted on one limb of the thermostat prevents the other limb from departing more than the 45 necessary short distance from its position of contact with the pilot tube tip 13', and thus prevents any distortion occurring upon cooling. For clearness, this is the position illustrated, notwithstanding that the flame is indicated as burning.

To start operation, there being no flame within at the pilot burner or the main burner, the pilot flame may be ignited with a match or by any suitable means, and burned 50 alone until the thermostat is heated suffi-

ciently to make and maintain the heat conducting contact. This occurs in a short time, ordinarily, and may be expedited by holding a match directly under the thermostat. Thereafter sufficient heat to maintain 70 the contact reaches the thermostat by conduction through the pilot burner tip section, when added to that coming by radiation from the flame and from the adjacent screen. The circuit is thus maintained continuously in 75 condition for the gas valve to be open, so long as the pilot flame 12 is burning. During this situation, the valve 16 may, however, be closed and opened ad libitum, either by hand, or automatically by the thermostat 80 22, or otherwise; and whenever that valve opens the gas that then flows out through the burner 10 will find the pilot flame 12 burning and ready to ignite it. But if for any reason the pilot flame 12 is extinguished, the thermostat 26 promptly opens the circuit between its point 29 and the pilot tube 13'; and while that condition continues 85 no current can pass through the circuit 20 to open the gas valve 16.

Figure 5 shows a form in which the heat is conducted from the flame through a separate rod or tube to the thermostat tip. In this case, the pilot tube is not a part of the circuit. The circuit may be further simplified, if desired, by making the tip continuous with the body part of the pilot tube, as indicated in Figure 4. In this case, the body of the tube and valve casing constitute part of the return circuit which is "grounded" 100 thereto.

Although the idea is illustrated as it may be used in connection with a pilot flame, whose normal function it is to be continuously burning, and against whose extinction the 105 device is a safeguard, it may be applied to any other sort of a gas flame, as for example, to a main burner, for protection in case of occurrence of a depression or cessation of main supply pressure sufficient to extinguish 110 the flame, followed by a restoration of such pressure.

We claim as our invention:—

1. The combination, with a gas burner and a service gas valve, of means to hold the 115 valve open; and a thermostat controlling said means; there being an element arranged to conduct heat to said thermostat from a flame associated with but independent of said burner; the said valve being arranged 120 to close automatically when not held open by said thermostatically controlled means.

2. The combination, with a gas burner and a service gas valve, of means to hold the 125 valve open; and a thermostat controlling said means; there being a strip of metal extending to the thermostat from a flame associated with but independent of said burner and conducting heat to said thermostat; the said valve being arranged to close automati- 130

cally when not held open by said thermostatically controlled means.

3. The combination, with a gas burner and a service gas valve, of means to hold the valve open; and a thermostat controlling said means; there being a tube for conducting gas to a pilot flame associated with said burner; the tube and thermostat being arranged for heat to flow by conduction through the tube from its flame to the thermostat; and said valve being arranged to close automatically when not held open by the thermostatically controlled means.

4. The combination, with a gas burner and a gas valve, of means to hold the valve open; and a thermostat controlling said means; there being a tube for conducting gas to a pilot flame associated with said burner; the tube and thermostat being arranged for heat to flow by conduction through the tube from its flame to the thermostat; and said valve being arranged to close automatically when not held open by the thermostatically controlled means; the said pilot tube having an electrically insulated heat and electricity conducting tip portion; and the said control means including an electric circuit of which said pilot tube tip is a part.

5. The combination, with a gas burner and a service gas valve, of means to hold the valve open; a thermostat controlling said means, arranged to receive and be actuated by heat from a flame associated with but independent of said burner; and means tending to retard escape of heat from said thermostat but not from the burner; the said valve being arranged to close automatically when not held open by said thermostatically controlled means.

6. The combination, with a gas burner and a gas valve, of means to hold the valve open; a thermostat controlling said means and arranged to be actuated by heat from a flame associated with but independent of said burner; and a screen encasing said thermostat, closely adjacent to the flame, conduct-

ing heat from the flame to the space around the thermostat and retaining heat of the thermostat; the said valve being arranged to close automatically when not held open by 50 said thermostatically controlled means.

7. The combination, with a gas burner and a gas valve, of means to hold the valve open; a thermostat controlling said means and arranged to be actuated by heat from a flame 55 associated with but independent of said burner; and an enclosure for the thermostat apart from the burner reducing the circulation of air thereabout; the said valve being arranged to close automatically when not held open by 60 said thermostatically controlled means.

8. The combination, with a gas burner and a gas valve, of means to hold the valve open; a thermostat controlling the said means, arranged to be actuated by heat from a flame associated with said burner; the said valve being arranged to close automatically when not held open by 65 said thermostatically controlled means; and a stop adapted to engage 70 the thermostat and prevent all but the initial part of the movement thereof which it tends to make when the flame is extinguished.

9. The combination, in a radiator, of heat radiating tubes; a gas burner set with gas therefrom escaping into the open air, and with openings arranged under the radiating tube entrances whereby normally gases from the burner flame are carried into said tubes; a valve controlling the supply to said burner; a pilot flame tube leading from the gas supply, before the valve, to a tip associated with said burner; said valve tending automatically to close; and means to hold the valve open, having a thermostat controlling 80 it, said thermostat being arranged to be actuated by heat from said pilot flame.

Signed at Providence, Rhode Island, this 27th day of October, 1919.
